UNITED STATES PATENT OFFICE.

AXEL AKERS, OF CHICAGO, ILLINOIS.

HIGH-PRESSURE STRAINER AND METHOD FOR CLEANING OR EXCHANGING THE STRAINER-BASKETS.

1,269,571.

Specification of Letters Patent. Patented June 18, 1918.

Application filed December 7, 1916. Serial No. 135,560.

To all whom it may concern:

Be it known that I, AXEL AKERS, a citizen of the United States of America, residing at Chicago, county of Cook, and State of Illinois, have invented new and useful Improvements in High-Pressure Strainers and Methods for Cleaning or Exchanging the Strainer-Baskets, of which the following is a specification.

10 The invention relates to high pressure strainers.

In power plants or pumping stations obtaining their water supply from lakes, rivers, creeks, or canals, means must be provided to separate solid foreign matter from

15 the water in order to obviate injurious effects on the pumps, condensers, or other plant machinery. The practice of placing large screens at the intake pipe has been

20 abandoned in view of the inaccessible location in which the screens invariably are placed, thus rendering necessary frequent cleaning unwarrantedly difficult. The later practice consisted in the replacing of the

25 flat screens by so-called twin strainers of the basket type, arranged in a valved housing. By the operation of two valves the strainers were alternately thrown in and out of service, so that the strainer basket not

30 in use could be subjected to cleaning or repairs.

While the present practice has certain undeniable advantages over the old method, it nevertheless does not meet the requirements

35 of high pressure systems, and the principal object of this invention consists in the provision of a high pressure strainer containing a plurality of baskets with fine mesh, which may be removed for cleaning or re-
40 pairs without entailing the necessity of reducing the pressure of the system, or in any manner interfering with the operation.

A further object consists in providing the strainer with additional chambers, termed
45 the charging and discharging chamber respectively, which normally are not in communication with the interior of the strainer, but may be placed in communication therewith when a defective or clogged basket is
50 to be moved thereinto.

Another object constitutes the provision of novel means for conveniently shifting a

basket into one of the additional chambers, from where it can be easily removed.

It is a further object of the invention to 55 provide means for equalizing the pressures in the additional chambers and in the interior of the strainer proper, prior to moving a repaired or cleaned basket into operative position, or moving a defective basket into 60 one of said chambers.

A still further object consists in the provision of additional chambers at both ends of the strainer, so that the chambers may be alternately used as charging and discharging chamber, in accordance with the location 65 of the defective strainer basket.

A further object constitutes the elimination of air pockets which reduce the effectiveness of suction set up by the engines, and 70 the obviation of all obstructions, other than the strainer baskets, in the path of the fluid.

It is also an object of the invention to provide certain details and features of construction and combinations tending to increase 75 the effectiveness and general desirability of a device of this particular character.

With these and other objects in view, the preferred embodiment of the invention consists in the novel combination and arrangement of parts to be hereinafter described and specifically pointed out in the appended claims. In the accompanying drawings,

Figure 1 is a top plan view of the improved strainer with parts broken away to disclose 85 the interior thereof.

Fig. 2 is a section on line 2—2 of Fig. 1.

Fig. 3 is a front elevational view of the strainer.

Fig. 4 is a section on line 4—4 of Fig. 1. 90

Referring to the drawings, 1 generally designates the main casing formed with an inlet opening 2, to which a suction pipe (not shown) is connected, and with an outlet opening 3, to which a delivery pipe (not shown) is connected, the other end of which is appropriately connected to a pump, condenser, or the like. The inlet opening 2 may communicate by means of the suction pipe with a suitable source of supply, such as a river, pond, or creek. A plurality of standards 4 and 5 serve to maintain the casing 1 in operative position, such that a plurality of strainer baskets 6 are held with

their longitudinal axes in horizontal position.

The casing is provided with an interior raceway 7 formed by a shoulder 8 and a longitudinally extending rib 9, arranged approximately midway between the inlet and outlet openings and directed downwardly and rearwardly from the upper wall of the casing. Similarly, a guide rib 10 extends 5 upwardly from the lower wall of the casing. By reference to Fig. 2 it will be noted that the upper wall of the casing in back of the basket strainers is flush with the highest point thereof, so that air pockets cannot exist. In the rib 9, a plurality of drain holes 8' are provided. To provide for the necessary clearance between the two baskets at the left-hand side respectively located in the chamber 24 and casing 1, so that the 10 valve 20' may be lowered into closing position, the handle 40 or the appertaining rod 35 is moved in proper direction, whereby the baskets in the casing recede from the basket in the chamber 24. Thereupon the valve 30' 15 may be closed. Similarly, in exchanging a defective basket at the right-hand side, handle 40 or the rod 35 adjacent to the chamber 23 is rotated to provide clearance between the baskets to enable the valve 29' to 20 be lowered into closing position. The basket strainers 6, in the form of cylinders, are made of a foraminous plate of any suitable material, such as brass, and are open at their rear end for the ingress of the water. The 25 forward end of the baskets is closed by a flaring portion 11, also perforated, so that water may have egress through the walls of the baskets or through the flaring portion 11.

As will be seen by reference to Fig. 2, the 30 strainer baskets are secured at their forward and rear ends to castings 12 and 13 respectively, by being riveted thereto or fastened in any other suitable or preferred manner. The casting 13 is in the form of a square 35 plate, the upper portion of which projects into the raceway 7 and bears against the longitudinal rib 9. The lower end is horizontally extended and rests on a plurality of bearing rollers 14 rotatably secured to the 40 vertical web of a longitudinally disposed channel iron 15 resting with one of its flanges on supports 16 projecting upwardly from the lower wall of the casing. The bottom of the casting 13, rearwardly of the 45 rollers 14, is formed with gear teeth constituting a rack 17 for a purpose hereinafter further explained.

The casting 12, as best shown in Fig. 3, forms a bearing for the lower part of the 50 strainer basket at its forward end, and is also secured thereto in any approved or suitable manner. This casting is supported by a plurality of rollers 18 rotatably secured to the vertical leg of an angle iron 19, longitudinally extending parallel to the channel

iron 15 and supported by bearings 20, which project upwardly from the lower wall of the casing. The casting 12 is also horizontally extended and is formed at the foremost portion of its bottom side with a rack 21. From the foregoing it is obvious that each strainer basket together with its castings forms an entity and is slidably supported on rollers 14 and 18.

In accordance with the object of the invention, provisions are made for the ready removal of defective or clogged strainer baskets to be repaired or cleaned, as the occasion requires. To this end the casing 1 is formed at both sides with an additional 75 chamber 23 and 24 respectively, which constitute a charging or discharging chamber for the removal or exchange of the baskets. As is indicated in the several views, the additional chambers are provided with rails 80 25 and 26 respectively provided with rollers 27 and 28, which are in alignment with the appertaining rollers of the main casing and on the level therewith. The additional chambers are separated from the interior 85 of the casing 1 by gate valves 29 and 30, which in the present case are manually actuated. It is, however, within the scope of this invention to devise special means for the operation of these gate valves, or to employ 90 motors whereby the valves are opened and closed in the course of operation. The chambers are closed at their outermost ends by doors 31, which may be secured in the closed position by pivotally arranged screw 95 rods 32, projecting through slotted arms 33 of the door, and by wing nuts 34.

At each end of the casing a transverse rod 35 is journaled in bearings 36 and 37, respectively secured to the channel iron 15 100 and angle iron 19. The rod 35 carries pinions 38 and 39 arranged and adapted to mesh with the racks 17 and 21 respectively, of the basket strainers. In order to facilitate rotation of the rods, handles 40 are secured thereto at their rearmost ends. In each of the additional chambers 23 and 24, a transverse rod 41 is journaled in bearings 42 and 43 secured to the rails 25 and 26. Pinions 44 and 45 are arranged level with 105 the pinions 38 and 39, and are also adapted to mesh with the appertaining racks of the strainer baskets. The rods 41 are each provided with a crank handle 46. At the lower side of the additional chambers an opening 47 and 48 respectively, is provided and serves to connect the delivery pipe leading to the pump or condenser (not shown) with the interior of an additional chamber, such as by means of a bleeder.

A defective or clogged strainer basket is removed in the following manner:

Let it be assumed that the basket at the left hand side, as viewed in Fig. 3, is to be removed and another basket to be installed. 130

- Both gate valves 29 and 30 are in closed position. The new basket is then introduced into the auxiliary chamber 23 by opening the door 31 which subsequently is closed and locked in closed position. Thereupon communication is established between the auxiliary chambers 23 and 24 and the delivery pipe (not shown) through the openings 47 and 48 whereby the pressures in the auxiliary chambers and the main casing are equalized. Subsequently both gate valves are opened and the crank handle 46 of the transverse rod 41 at the right hand side is turned. In the chamber 23 the strainer basket, of course, rests with its castings 12 and 13 on the rollers 26 and 27. By virtue of the pinions 44 and 45 meshing with the racks of the strainer basket, the latter is shifted into the main casing, provided the 20 crank handle is moved in the proper direction and, as will be readily understood, the series of baskets in the casing are also displaced. Thus the basket formerly located at the left hand side of the casing and which 25 is to be replaced, is now forced into the auxiliary chamber 24, while the added basket occupies the position at the right hand side in the casing, the said baskets occupying corresponding positions within the casing. Having thus shifted the strainer baskets, the gate valves are closed and the communication between the auxiliary chambers and the delivery pipe is terminated. The door of the auxiliary chamber 24 can then 30 be opened and the defective basket located therein can be removed for repairs.
- The same procedure takes place, for instance, when the right hand basket, as viewed in Fig. 3, becomes defective or 35 clogged, but in such case the additional chamber 24 becomes the charging chamber, while the chamber 23 assumes the function of the discharging chamber.
- The ease with which the strainer baskets 40 may be exchanged or replaced is a striking feature of the invention, in view of the fact that in high pressure systems cleaning of the baskets must be effected at frequent intervals and forms an important part in the 45 operation of pumping stations or power plants in general. It is furthermore significant that there is no obstruction offered to the flow of the fluid while changing the baskets. The strainer area is not reduced by 50 a gate valve or other means, in order to substitute a new basket for a clogged one. The latter quality of the improved device is of special value, as in view of the reduced strainer area and the increased friction on 55 the remainder of the apparatus the output of the entire device cannot be appreciably curtailed.
- While the drawings illustrate the preferred embodiment of the invention, it is, 60 of course, understood that the details of construction and arrangement, as shown, are capable of changes and variations, and for this reason I do not confine myself thereto, but want to avail myself of such departures of construction and arrangement which 65 fairly fall within the scope of the invention, as indicated in the appended claims.
- I claim:
1. A high pressure strainer comprising a casing having an inlet and outlet opening, a series of strainer baskets arranged in said casing, auxiliary chambers arranged at both ends of the strainer, and means for moving said baskets whereby one enters the adjacent one of said chambers. 70
  2. A high pressure strainer comprising a casing having an inlet and outlet opening, a series of strainer baskets arranged in said casing, auxiliary chambers arranged at both ends of said casing, means for slidably supporting said strainers, and means for moving said baskets whereby one enters the adjacent one of said chambers. 80
  3. A high pressure strainer comprising a casing having an inlet and outlet opening, auxiliary chambers arranged at both ends of said casing, a series of strainer baskets arranged in said casing with the longitudinal axes in horizontal position, castings provided at both ends of said baskets and secured thereto, rails extending longitudinally of said casing, bearing rollers on said rails supporting said castings, and means for moving said baskets whereby one enters the adjacent one of said auxiliary chambers. 90
  4. A high pressure strainer comprising a casing having an inlet and outlet opening, said casing being formed with a longitudinal raceway, auxiliary chambers at both ends of said casing, a series of strainer baskets arranged in said casing with their longitudinal axes in horizontal position, castings provided at both ends of said baskets and secured thereto, one of said castings projecting into said raceway, rails extending longitudinally of said casing, bearing rollers on said rails, said castings being supported by said bearing rollers, and means for moving said baskets whereby one enters the adjacent one of said auxiliary chambers. 100
  5. A high pressure strainer comprising a casing having an inlet and outlet opening, a series of strainer baskets arranged in said casing, auxiliary chambers arranged at both ends of said casing, means for placing said chambers in and out of communication with said casing, and means for horizontally moving said baskets whereby one enters the adjacent one of said chambers. 110
  6. A high pressure strainer comprising a casing having an inlet and outlet opening, a series of strainer baskets arranged in said casing, auxiliary chambers arranged at both ends of said casing, valves interposed between said casing and said auxiliary chambers. 120
  7. A high pressure strainer comprising a casing having an inlet and outlet opening, a series of strainer baskets arranged in said casing, auxiliary chambers arranged at both ends of said casing, valves interposed between said casing and said auxiliary chambers. 125
  8. A high pressure strainer comprising a casing having an inlet and outlet opening, a series of strainer baskets arranged in said casing, auxiliary chambers arranged at both ends of said casing, valves interposed between said casing and said auxiliary chambers. 130

bers, and means for horizontally moving said baskets, whereby one enters the adjacent one of said chambers.

7. A high pressure strainer comprising a casing having an inlet and outlet opening, a series of strainer baskets arranged in said casing, auxiliary chambers arranged at both ends of said casing, valves interposed between said auxiliary chambers and said casing, said strainer baskets being arranged with their longitudinal axes secured in horizontal position, castings provided at both ends of said baskets and secured thereto, rails extending longitudinally of said casing, bearing rollers on said rails, said castings being supported by said bearing rollers, and means for moving said baskets whereby one enters the adjacent one of said chambers.

8. A high pressure strainer comprising a casing having an inlet and outlet opening, said casing being formed with a longitudinal raceway, auxiliary chambers arranged at both ends of said casing, valves interposed between said casing and said chambers, a series of strainer baskets arranged in said casing with their longitudinal axes in horizontal position, castings provided at both ends of said baskets and secured thereto, one of said castings projecting into said raceway, rails extending longitudinally of said casing, bearing rollers on said rails, said castings being supported by said bearing rollers, and means for moving said baskets whereby one enters the adjacent one of said chambers.

9. A high pressure strainer comprising a casing having an inlet and outlet opening, auxiliary chambers arranged at both ends of said casing, a series of strainer baskets arranged in said casing with their longitudinal axes in horizontal position, castings provided at both ends in said baskets and secured thereto, rails extending longitudinally of said casing, additional rails extending longitudinally of said chambers and in alinement with said first named rails, bearing rollers on all of said rails, said castings being supported by said bearing rollers and means for moving said baskets whereby one enters the adjacent one of said auxiliary chambers.

10. A high pressure strainer comprising a casing having an inlet and outlet opening, a series of strainer baskets arranged in said casing, auxiliary chambers arranged at both ends of said casing, means for placing said chambers in and out of communication with said casing, means enabling the equalization of pressures in said casing and said auxiliary chambers, prior to establishment of communication, and means for horizontally moving said baskets whereby one enters the adjacent one of said chambers.

11. A high pressure strainer comprising a casing having an inlet and outlet opening,

said casing being formed with a longitudinal raceway, auxiliary chambers at both ends of said casing, valves interposed between said casing and said chambers, a series of strainer baskets arranged in said casing with their longitudinal axes in horizontal position, castings provided at both ends of said baskets and secured thereto, one of said castings projecting into said raceway, rails extending longitudinally of said casing, additional rails extending longitudinally of said chambers and in alinement with said first named rails, bearing rollers on all of said rails, said castings being supported by said rollers, and means for moving said baskets whereby one enters the adjacent one of said auxiliary chambers.

12. A high pressure strainer comprising a casing having an inlet and outlet opening, said casing being formed with a longitudinal raceway, auxiliary chambers at both ends of said casing, valves interposed between said casing and said chambers, means enabling the equalization of pressures in said casing and said auxiliary chambers when said valves are closed, a series of strainer baskets arranged in said casing with their longitudinal axes in horizontal position, castings provided at both ends of said baskets and secured thereto, one of said castings projecting into said raceway, rails extending longitudinally of said casing, additional rails extending longitudinally of said chambers and in alinement with said first named rails, bearing rollers on all of said rails, said castings being supported by said rollers, and means for moving said baskets whereby one enters the adjacent one of said auxiliary chambers.

13. A high pressure strainer comprising a casing having an inlet and outlet opening, auxiliary chambers at both ends of said casing, a series of strainer baskets arranged in said casing with their longitudinal axes in horizontal position, a casting provided at both ends of said baskets and secured thereto, means for slidably supporting said castings, said castings being formed with racks, and means engaging said racks for shifting said baskets, whereby one enters the adjacent one of said chambers.

14. A high pressure strainer comprising a casing having an inlet and outlet opening, auxiliary chambers at both ends of said casing, a series of strainer baskets arranged in said casing with their longitudinal axes in horizontal position, castings provided at both ends of said baskets and secured thereto, rails extending longitudinally of said casing, bearing rollers on said rails supporting said castings, said castings being formed with racks, and means engaging said racks for shifting said baskets whereby one enters the adjacent one of said chambers.

15. A high pressure strainer comprising

1. A casing having an inlet and outlet opening, said casing being formed with a longitudinal raceway, auxiliary chambers at both ends of said casing, said chambers being provided with doors, valves interposed between said casing and said chambers, means enabling the equalization of pressures in said casing and said auxiliary chambers, a series of strainer baskets arranged in said casing with their longitudinal axes in horizontal position, castings provided at both ends of said baskets and secured thereto, one of said castings projecting into said raceway, rails extending longitudinally of said casting, additional rails extending longitudinally of said chambers and in alignment with said first named rails, bearing rollers on all of said rails supporting said castings, said castings being formed with racks, and means engaging said racks for shifting said baskets whereby one enters the adjacent one of said chambers, substantially as described.
2. A high pressure strainer comprising a casing having an inlet and outlet opening, a series of strainer baskets arranged in said casing, auxiliary chambers arranged at both ends of said casing, valves interposed between said casing and said chambers, and means for selectively moving the end baskets of said series into the appurtenant auxiliary chamber.
3. A high pressure strainer comprising a casing having an inlet and outlet opening, a series of strainer baskets arranged in said casing, auxiliary chambers arranged at both ends of said casing, valves interposed between said casing and said chambers, and means arranged at the casing and at the auxiliary chambers for selectively moving said baskets horizontally.
4. A high pressure strainer comprising a casing, a series of strainer baskets arranged in said casing, auxiliary chambers adapted to be placed in communication with said casing, and means for adding one basket to the series and displacing another into the adjacent one of said chambers.
5. In a high pressure strainer, a casing containing a series of strainer baskets, auxiliary chambers adapted to be placed in communication with said casing, and means for adding a basket to the series and thereby forcing another from said casing into an adjacent one of said chambers.

In testimony whereof I affix my signature.

AXEL AKERS.
